Patented Oct. 6, 1914.

UNITED STATES PATENT OFFICE.

FRANK R. WHITTLESEY, OF OAKLAND, CALIFORNIA.

ELECTRIC HEATER.

1,112,582.

Specification of Letters Patent.

Patented Oct. 6, 1914.

Application filed October 7, 1913. Serial No. 793,948.

To all whom it may concern:

Be it known that I, FRANK R. WHITTLESEY, a citizen of the United States, residing at Oakland, in the county of Alameda and State of California, have invented certain new and useful Improvements in Electric Heaters, of which the following is a specification.

My invention relates to the general class of electric-heaters. It is adapted for heating devices of various kinds, but particularly for those which, from the nature of their use, such, for example, as radiators for warming rooms, and, particularly, as cookers, require to receive and to impart different degrees of heat, according to circumstances.

The object of my invention is to provide a simple and effective electric-heater for these and like purposes; and to this end my invention consists in the novel heater which I shall now fully describe by reference to the accompanying drawings, in which—

Figure 1 is a perspective view of my heater. Fig. 2 is a perspective view of the heating member showing its grooved upper face. Fig. 3 is a bottom plan of the heating member showing its grooved lower face. Fig. 4 is a section, enlarged, through the heating member on the line $x-x$ of Fig. 2, this figure showing also, in section, the inclosing box and the asbestos protection of the heating wire.

1 is the heating member. It consists of a plate or body of low electric and heat conductivity. It may be of any suitable material or combination of materials having such property. In practice, I employ a slab of Portland-cement or concrete. In this plate 1, in its upper surface, as seen in Fig. 2, are formed the grooves 2 for the electric heating wire, and in its lower surface, as seen in Fig. 3, are formed similar grooves 3. In case a concrete slab is used, these grooves are best molded in the material. The grooves may be directed in any suitable extensive, tortuous course, in order to cover practically the superficial area of the slab. They are best formed in the continuous return or zig-zag course shown. In the upper face the groove 2 begins at one end of the slab, as shown in Fig. 2, and thence extends back and forth, with its turns near but not reaching nor exposed to the ends, to the opposite side of the slab where it opens out in the same end of the slab and passes

down in said end and joins the beginning of the groove 3 of the lower face, by means of a short vertical groove 4 in said end. The lower groove 3, as shown in Fig. 3, returns 60 in the lower face of the slab in similar manner, to the first side, where it opens out in the same end in which the upper groove started.

5 is the wire for conducting the electric 65 current. It starts in the groove 2 at its beginning and is then laid throughout the course of said groove, thence passes down the vertical connecting groove 4 to the lower groove 3, in which it returns to the exit of 70 said lower groove.

In the end of the slab 1, at the beginning of the groove 2 is made the permanent electrical connection, indicated at the point 6 in Fig. 1, with the beginning of the heating 75 wire 5. In the end of the slab at the opposite side of said end is a socket 7 adapted to receive an electric plug connection with the wire 5 as it passes down in the vertical connecting groove 4. In the same end of the 80 slab at one or more points between its sides, here shown, for the sake of illustration, as at one point, is a socket 8 for the reception of an electric plug connection, with the lower wire course in the lower groove 3. 85 Finally at the first side of the slab end is a socket 9 to receive an electric plug connection with the issuing end of the heating wire 5.

10 indicates asbestos or other like material 90 for sealing the wire 5 in its grooves and protecting it from contact with the exterior casing or box of the slab.

11 is an iron casing or box with legs 12. This box comprises a bottom and sides and 95 ends, the latter rising above the slab and receiving between them the removable iron top-plate 13. In one end of this box are made openings 14 which register with the several sockets in the slab end, so that the 100 plug connections, heretofore mentioned, can be made.

15 is a double electric cord leading from the source of electric current. The end of one cord is permanently connected at 6, in 105 Fig. 1, with the beginning of the wire 5. The other cord carries a plug 16, adapted to fit any of the sockets 7, 8 or 9. When the plug 16 is fitted to the socket 7, the electric current flows only through the upper wire 110 course, and having the least resistance, will impart to the slab 1, the highest heat. When

the plug 16 is fitted to the socket 9, the current flows through both upper and lower wire courses, and having the greatest resistance will give to the slab 1, the lowest heat. When said plug 16 is fitted to the socket 8, the current will flow through a part only of the lower wire course and through the entire upper course, and will impart to the slab an intermediate heat. Therefore, in operating the device, different heats may be obtained, as desired. For example, in using the device as a cooker, the plug 16 will first be fitted to the socket 7 so that the slab 1 may be quickly and highly heated. Then, when sufficiently heated, the slab, on account of its low conductivity and its ability to retain heat, may well have its heat increment reduced, and this may be done by fitting the plug to the socket 8, or, in case the lowest heat be sufficient, the plug will be inserted in the socket 9.

I claim:—

1. An electric-heater comprising a heating member of low electric and heat conductivity, said member having formed in its upper and lower faces a continuous tortuous groove the ends of which emerge from the member at one end near one side thereof, one above the other; and the middle portion passing from the upper to the lower face in said end near the other side thereof, said end being formed with plug-receiving sockets at the ends of the groove and at points intermediate said ends; an electric wire seated in said groove and exposed for electrical contact in the sockets of said member; a double electric cord one cord of which is electrically connected with the beginning of the electric-heating-wire; and a plug carried by the other cord adapted to be fitted at will to any of the sockets of the heating member, to make electrical contact with the heating wire at various points in the length of said wire.
- 45 2. An electric-heater comprising a heating member of low electric and heat conductivity, said member having formed in its

upper and lower faces a continuous tortuous groove the ends of which emerge from the member at one end near one side thereof, one above the other, and the middle portion passing from the upper to the lower face in said end near the other side thereof, said end being formed with plug-receiving sockets at the ends of the groove and at points intermediate said ends; an electric wire seated in said groove and exposed for electrical contact in the sockets of said member; a metallic box inclosing said heating member said box having openings registering with the sockets of said member; means for insulating the heating wire from the metallic box; a double electric cord one cord of which is electrically connected with the beginning of the electric-heating-wire; and a plug carried by the other cord adapted to be fitted at will to any of the sockets of the heating member, to make electrical contact with the heating wire at various points in the length of said wire.

3. An electric heater comprising a substantially rectangular block formed on each of its faces with a tortuous groove, the groove of one face communicating with the groove of the other face, a heating wire lying in said groove, a casing receiving the block, a closure for the casing, a filling of asbestos interposed between the faces of the block and the casing, said asbestos entering the grooves formed in said faces, there being openings formed in the casing which align with openings formed in the edges of the block whereby to permit of the insertion of an electric connection to effect a connection with the heating wire at different points throughout its length to increase or diminish the resistance.

In testimony whereof I have signed my name to this specification in the presence of two subscribing witnesses.

FRANK R. WHITTLESEY.
